SLICING MACHINE

Xan B. K. Green, New Paltz, and Harry Preble, Jr., Cross
River, N. Y., assignors to General Slicing Machine Co.,
Inc., Walden, N. Y., a corporation of New York

Application July 7, 1953, Serial No. 25,821

Term of patent 14 years

(Cl. D55—1)

To all whom it may concern:

Be it known that we, Xan B. K. Green and Harry Preble, Jr., citizens of the United States of America, residing respectively at the city of New Paltz, county of Ulster, State of New York; and at the city of Cross River, county of Westchester, and State of New York, have jointly invented the new, original, and ornamental Design for a Slicing Machine, of which the following is a specification, reference being had to the accompanying drawings, forming part thereof, wherein Fig. 1 is a perspective view of a slicing machine showing our new design; said view being taken looking at the front of the machine and one side thereof. Fig. 2 is a perspective view of said machine as seen from the front and the

other side thereof and Fig. 3 is a perspective view of said machine as seen from the rear and the first mentioned side thereof.

We claim:

The ornamental design for a slicing machine, substantially as shown.
